UNITED STATES PATENT OFFICE.

EDWARD A. ROCKWELL, OF NEW HAVEN, CONNECTICUT, ASSIGNOR TO E. A. ROCKWELL COMPANY, INC., OF NEW YORK, N. Y., A CORPORATION OF NEW YORK.

VACUUM FEEDING APPARATUS.

1,415,195.

Specification of Letters Patent. Patented May 9, 1922.

Application filed July 16, 1918. Serial No. 245,216.

To all whom it may concern:

Be it known that I, EDWARD A. ROCKWELL, a citizen of the United States, and a resident of New Haven, in the county of New Haven and State of Connecticut, have invented certain new and useful Improvements in Vacuum Feeding Apparatus, of which the following is a specification.

The invention made is in the simplification, construction, and operation of vacuum feeding apparatus. This apparatus is used particularly as an automobile accessory. It may as well find uses in other arts where it is desired to feed liquids from one level to another with the main tank or reservoir at a level below the level of the point of needed supply. This is important where the liquid is dangerous, as in all gasoline storage and supply apparatus.

The invention's object is to eliminate the need for mechanical contrivances, such as springs, levers and like moving parts, as far as possible. I accomplish the desired result by an arrangement of my apparatus whereby the natural laws of gravity, buoyancy, and atmospheric pressure may be utilized to my end more directly than heretofore thought possible. The operating mechanism is thus simplified to such an extent that at once it becomes more positive in action, more easily manufactured, durable and dependable in use.

A further object is to provide but one float-operated valve and in such a way as to completely render unnecessary all toggles, springs, vacuum shut-off valves, etc., as now commonly used and at the same time make my one valve readily accessible from the outside, without dismantling any other part of the device.

I utilize a gravity chamber open to the atmospheric pressure, a vacuum chamber, and a simple valve to automatically permit gravity feed to the former chamber from the latter chamber when the pressure in each is substantially equal and to prevent such feed when the pressures are unequal. The vacuum chamber is arranged to be open to a subnormal pressure chamber by a connection, for example, with the intake manifold of a running engine, and is also arranged to be sometimes open to atmospheric pressure whereby the influence of the subnormal pressure is substantially overcome. The vacuum chamber has a connection for liquid

to feed from the low level main supply tank under atmospheric pressure to the vacuum chamber when the latter is open to the subnormal pressure. With these chambers arranged for connections as stated, the general or common purpose of a vacuum feed system will be accomplished if the pressure in the vacuum chamber is changed alternately from subnormal to normal atmospheric pressure, whereby the liquid may first feed to such chamber and then from it to the gravity chamber. The main requirement, then, for the purpose is to automatically change the pressure conditions in the vacuum chamber as and when the feed of fluid is required.

I satisfy this requirement, according to one feature of my invention, by inserting a float of high buoyancy value for action in the liquid of the vacuum chamber. I attach to this float or provide on the float itself means to lift, by reason of the float's buoyancy, a pressure inlet valve for the vacuum chamber directly and against atmospheric pressure, and this is accomplished without intermediate or relatively moving parts commonly used between the float and valve. The preferred action for which I provide in opening the valve depends, first, on a subnormal vacuum chamber pressure and a consequent rise of liquid level therein due to the feed from the main tank. This causes a rise of the float and an early engagement of the valve. Thereafter, the float can not immediately rise further, even though the liquid level does. The increased immersion of the float in the liquid increases the buoyancy until it is sufficient to overcome the atmospheric pressure holding the valve closed. Then the valve is opened and at a time designed for the liquid level in the vacuum chamber to be at its high point. Once such valve is open, the subnormal pressure in the vacuum chamber becomes normal and the liquid flows to the gravity chamber through the gravity or check valve. The buoyant float, however, holds the pressure inlet valve open even though the liquid level is falling in the vacuum chamber due to the fact that the float had to acquire a buoyancy due to a rise in liquid level sufficient to open the valve against pressure. Since the valve is opened, the buoyancy to hold it open is considerably less than that which was required to open it, so that until the liquid level falls sufficiently to per-

mit the float to fall with it the valve will be held open. Thereafter it will be closed and the cycle repeated. This action, then, due to conditions, provide effectively for an 5 intermittent opening and closing of the pressure inlet valve with a timed interval designed to permit liquid to flow to and from the vacuum chamber and a desired feed to the gravity chamber. The whole operation 10 is characterized by the physical laws employed for the purpose and by a remarkably simple arrangement.

Other features of the invention will appear in the detailed description of one preferred form of its embodiment, but such 15 description is not intended to limit the scope of my invention except as the prior art and the claims properly interpreted thereby may require.

20. In the drawings,—

Fig. 1 is a longitudinal sectional view through the apparatus showing the main arrangement and parts in detail;

Fig. 2 is a top plan view;

25 Fig. 3 is a section on the line 3—3 of Fig. 1;

Fig. 4 is a section on the line 4—4 of Fig. 1; and

30 Fig. 5 is a diagrammatic view showing the general arrangement of the vacuum feed apparatus in connection with the main supply tank, a carbureter, and the intake manifold of an explosive engine.

As shown, a main tank 1 is divided by a 35 horizontal wall 21 into two chambers 2 and 3. I term chamber 3 the "gravity" chamber because it is at all times open to atmospheric pressure and the liquid flows by gravity to and from this chamber 3. The 40 chamber 2 above the horizontal wall 21 I term a "vacuum" chamber because the pressure within this chamber is at the proper time and under the proper conditions below atmospheric pressure and thus, on the vacuum principle, the liquid is fed under atmospheric pressure to this chamber 2 from the main supply tank 25 at a lower level than the chamber 2. The top of the chamber 2 is closed by means of a casting 16 45 fastened to the walls of the tank 1 in any suitable manner.

Through this casting there is an opening 14 for the fuel feed, a valve-controlled opening 30 to the atmosphere for chamber 2, an opening 21 communicating with the connection 20 between the chamber 2 and the intake manifold 27 of the explosive engine, and an opening 19 for the pipe or tube 11 to keep the gravity chamber 3 in communication with the atmosphere at all times. These openings are in some cases screened, as by screen 23, and, in general, such openings and their primary purpose are well understood by one skilled in the art.

60 65 The gravity chamber 3 has an opening

at the bottom normally closed by screw-threaded plug 12, whereby the tank may be drained and cleaned as desired. Also, at the bottom of this tank there is the normally open connection with the pipe 13 70 which, as shown in Fig. 5, leads to the carbureter 26 to feed the latter by gravity. A pipe connection 6 serves as a communication between chambers 2 and 3 and is mounted in the wall 21 to provide means for conveniently applying a valve 5 to such communication and also conveniently hold a spider-guide 7 within which the operating rod 8 mounted on to move with the float 9 is guided.

80 The valve 5 is an ordinary flap valve which may be mounted generally as shown and may open to permit liquid to flow from chamber 2 through pipe 6 to chamber 3 when the pressures within the two chambers 85 are substantially equal. The specific form of this valve 5 is not important, except that it should open by gravity and be mounted as shown and indicated to close when the pressure in chamber 3 is greater than the 90 pressure in chamber 2.

The valve 22 is adapted to close the passage leading to the opening 24 leading directly to the outer air and may be conveniently mechanically depressed and held 95 lightly against its seat by means of a light spring 30 arranged between the valve and a screen 23 screw-threaded on the boss as indicated. Within the passage leading to the opening 24 the rod 8 is cut down at its ends 100 to a triangular shape, as shown in Fig. 3, whereby the pressure within the tank 2 will be on one side of the valve 22 while the atmospheric pressure will be on the other or outer side.

105 Within the chamber 2 and arranged on and concentrically with the rod 8 there is a float 10 which I preferably make of cork properly treated, as by shellac, to withstand the action of gasoline or other liquid which 110 may pass through the apparatus. The upper end of this float is large, as indicated, while depending from the enlarged end is a cylindrical portion 9. By this arrangement, I provide a float of very considerable buoyancy and one which will at practically all times have a considerable part of its volume within the liquid at whatever level the latter may be. The rod 8 moves up and down with the float 10, properly 115 guided in straight-line movement by the spider 7 and the fact that the end of the rod 8 is guided in the opening 30 below valve 22 and spring.

120 With the parts arranged as described and of the simple character indicated, the operation will be readily understood from what follows. Assume that the apparatus is connected as indicated in Fig. 5 and with the engine to which the manifold 27 is con- 130

nected running; the subnormal pressure in the manifold 27 will cause a like subnormal pressure within the chamber 2 by reason of the connection 20. The liquid in the tank 5 25, however, is under atmospheric pressure and this condition causes the gasoline to feed through pipe 17 and opening 14 to chamber 2.

As the chamber 2 fills, the float 10 rises 10 and moves the rod 8 against the valve 22. At the same time, pressure in the gravity chamber 3 is, by reason of the connection 11 and opening 19, at atmospheric pressure and therefore greater than the pressure in the 15 chamber 2. This condition causes the valve 5 to be closed tightly against its seat and prevents liquid from passing through pipe connection 6 and opening 4 to the chamber 3. Whatever gasoline there is already in 20 chamber 3, however, may, of course, feed normally through pipe 13 to the carburetor 26 to keep the engine running. The float 10, when it has been moved by the liquid entering chamber 2 so that the rod 8 presses 25 against the valve 22, stops because some little force beyond that given by the buoyancy of the float at this level of the liquid is required to open the valve 22. This is so because the pressure on one side of the valve is 30 less than atmospheric pressure while the pressure on the other side of the valve is equal to atmospheric pressure. The liquid continues now to enter the chamber 2 and increase the buoyancy of the float 10 by 35 reason of the fact that an increased portion of the buoyant float is submerged in the liquid. In this manner the force due to the buoyancy of the float gradually becomes sufficient to open the valve 22 against the pressure stated, and as soon as the valve 22 is 40 open then the pressure within the chamber 2 becomes equal to the atmospheric pressure, or substantially so, because the suction from the manifold 27 through pipe 20 cannot take 45 away the air as fast as it enters.

As soon as the chamber 2 is open to atmosphere, then the pressure of the liquid acting through the opening 4 is sufficient to open valve 5 and the liquid starts to feed by 50 gravity to chamber 3. The valve 22 will not close as the liquid level begins to fall in chamber 2, for the reason that it will be remembered that the float 10 came to stop against the valve 22 before the liquid level 55 stopped rising in chamber 2 in the first part of the cycle. Thus, it is necessary for the liquid level in chamber 2 to fall to a substantial degree before the float 10 loses the buoyancy necessary to keep the valve 22 60 open, inasmuch as such buoyancy now does not have to act against any counteracting pressure except that of gravity and the light spring 23, which may not be considered as substantial in this connection. The liquid 65 level continues to fall in chamber 2 and the

liquid to pass into chamber 3 until the valve 22 is closed and the suction from the manifold 27 causes a decrease in the pressure within chamber 2 sufficient to cause the atmospheric pressure in chamber 3 to close the 70 valve 5. When the latter closes, the operations are repeated.

It is important to note, as will be emphasized in the embodiment and description of the invention shown, that there is a substantial delayed action in the opening and closing of valve 22 and that this delayed action is characterized by pressures and float-buoyancy conditions to a far greater degree than by the mechanics of moving 75 parts. Thus, the desired result is accomplished in an extremely simple manner. The only moving parts in the apparatus are the valve 22 of the simplest form, the float 10 and its attached rod 8 moving therewith 80 but not with relation thereto, and the valve 5. Such movements as occur are substantially straight-line movements. The only care required in manufacture and maintenance beyond ordinary pipe fitting is to 85 see that valve 22 is tight. The removal of fitting 31 permits access to valve 22 and its seat without any other operation. The embodiment of the apparatus disclosed as well as the invention generally is characterized 90 by the skill shown in its design rather than the skill necessary to manufacture it and 95 keep it going.

It will, of course, be understood from the general description of the invention that the 100 valve 22 may be opened and kept open for the desired time by designing the area of the valve on which the atmospheric pressure bears compared to the area of the valve exposed to the pressure within the chamber 2. 105 Also, the time may be controlled by the design of the float 10 and the degree of its buoyancy.

The features of the invention may be utilized in other ways than that shown in the 110 preferred embodiment of it, but it is not thought necessary to show such variations as might properly come within the scope of the invention as now claimed.

I claim as my invention:

1. A vacuum feed apparatus having in combination, a tank or chamber designed to receive liquid under subnormal pressure and discharge it under normal pressure and pressure-controlling means for said chamber to alternately permit and then prevent subnormal pressure therein comprising a valve located in an opening from the chamber to normal pressure, a float of high buoyancy 120 value in the liquid of the chamber, and means immovably carried by the float and in early engagement with said valve to directly and operatively connect the float and valve whereby the liquid in the chamber must rise 125 to a level sufficient to immerse the float for 130

4
a buoyancy value to open the valve against atmospheric pressure before said valve can open and fall to a level sufficient to immerse the float for a less buoyant value to fall 5 with the liquid before said valve can close.

2. A vacuum feed apparatus, comprising in combination a vacuum tank and means including a valve to intermittently change the pressure therein at timed intervals according to the liquid level in the tank, such means including a regulating float of high buoyancy value arranged to directly operate said valve, and a device to cause the float to act as a regulator by a comparatively 10 wide range of increase and decrease in the buoyancy value of the float under the rise and fall of liquid with respect to the float.

3. A vacuum feed apparatus comprising, a vacuum tank or chamber, a regulating float therein and a pressure-controlled valve member having direct engagement with and causing the float to act by a comparatively wide range of increase and decrease in buoyancy value as the liquid rises and falls 25 in the chamber with respect to the float.

4. A vacuum feed apparatus comprising, a vacuum tank or chamber, a lift valve in an opening to the atmosphere from the chamber arranged to have a substantial area 30 for atmospheric pressure to hold it closed, a float within the chamber designed to have its buoyancy force directly balance such atmospheric pressure at the time when the valve should open, said float being formed and arranged to exert pressure on and maintain 35 immovable relation with said valve through the entire chamber-filling operation.

5. For the purpose described, a tank and a substantially T-shaped float therein to insure 40 a substantial body immersion under the conditions described, the cross-sectional area of the head portion and of the stem portion of the float being unchanged throughout their respective lengths.

45 6. A vacuum feed apparatus, comprising a vacuum tank or chamber having an open-

ing to the atmosphere and a valve for said opening entirely accessible from outside the chamber, an opening from the chamber to a region of subnormal pressure, said first-named opening being sufficient in size to render the influence of the second opening negligible when the valve of the former opens, and a float within the chamber relatively immovable with relation to said valve and arranged to transmit its functional movement directly to the said valve to open the same.

7. A vacuum feed apparatus comprising a vacuum tank or chamber connected by a 60 passage to a region of subatmospheric pressure and having an opening to the atmosphere of greater cross-sectional area than that of said passage, a valve controlling the opening, a float of T-shaped vertical section 65 in the tank, means connected to the float for operating the valve, and a fuel intake and exit port in the tank.

8. A vacuum feed apparatus comprising a vacuum tank or chamber connected by a passage 70 to a region of subatmospheric pressure and having an opening to the atmosphere of greater cross-sectional area than that of said passage, a lift valve controlling the opening, a single float of T-shaped vertical 75 section in the tank, a vertical rod on the float for lifting the valve, and a fuel intake and exit port in the tank.

9. A vacuum feed apparatus comprising a vacuum tank or chamber connected by a passage 80 to a region of subatmospheric pressure and having an opening to the atmosphere of greater cross-sectional area than that of said passage, a valve controlling the opening, a float of T-shaped vertical section in 85 the tank, means connected to the float for operating the valve, a fuel intake for the tank, a second tank open to atmosphere and connected by a passage to the first tank with a vertical flap valve in the passage, and an 90 exit port in said second tank.

EDWARD A. ROCKWELL.
